(57) **CLAIM**

The ornamental design for a beverage container, as shown and described.

DESCRIPTION

FIG. 1 is an elevational view of a beverage container showing my new design;

FIG. 2 is a top plan view of the beverage container of FIG. 1; and,

FIG. 3 is a bottom plan view of the beverage container of FIG. 1.

The ornamental design that is claimed is shown in solid lines in the drawings. Elements shown in broken lines form no part of the claimed design.
